UNITED STATES PATENT OFFICE.

ERNST G. K. ANDERSON, OF CHICAGO, ILLINOIS, ASSIGNOR, BY MESNE ASSIGNMENTS,
TO APPLETON ELECTRIC CO., OF CHICAGO, ILLINOIS, A CORPORATION OF ILLINOIS.

ELECTRIC SWITCH.

Application filed June 30, 1919. Serial No. 307,650.

To all whom it may concern:

Be it known that I, ERNST G. K. ANDERSON, a citizen of the United States, and a resident of Chicago, in the county of Cook and State of Illinois, have invented certain new and useful Improvements in Electric Switches; and I do hereby declare that the following is a full, clear, and exact description thereof, reference being had to the accompanying drawings, and to the characters of reference marked thereon, which form a part of this specification.

This invention relates to improvements in electric switches and refers more particularly to that form of switch illustrated in my prior application for United States Letters Patent Serial Number 226,419, filed April 3, 1918, wherein the actuating device for the switch is so constructed and associated with the switch elements that the switch is opened and closed by the same movement of said actuating device, regardless of whether the switch be opened or closed at a given time. As shown in said prior application, the movement of the actuating device is a universal swinging movement and also an axial movement; and the actuating device is automatically restored to normal position after each operation. Associated with the movable switch element or blade is a spring element which serves, upon operation of the actuating device, to quickly throw the switch blade past its center of movement and to its full open or its full closed position, the actuating device being automatically restored to position to reverse the direction of throw of the switch blade in the next operation thereof.

The present invention relates to improvements which adapt the essential elements of my aforesaid invention to a given switch structure.

In the drawings,

Figure 1 is a vertical section of a switch and its switch mounting, on the line 1—1 of Figure 3.

Figure 2 is a vertical section thereof on the line 2—2 of Figure 1.

Figure 3 is a horizontal section on the line 3—3 of Figure 1.

Figure 4 is a vertical section on the line 4—4 of Figure 3, looking in the direction of the indicating arrows.

Figure 5 is a perspective view of the switch blade mounting frame.

Figure 6 is a perspective view of the switch actuating plunger.

Figures 7 and 8 are fragmentary details illustrating the essential elements of the switch mechanism in different positions.

Figure 9 is a plan view of the swinging switch blade.

Figures 10 and 11 are details of said blade, Figure 10 being taken on the line 10—10 of Figure 11, and Figure 11 being an edge elevation of said blade.

Figure 12 is a perspective view of a controller member of the switch reversing element.

Figure 13 is a perspective view of a spring actuated switch blade throw-over plunger.

Figures 14 and 15 are, respectively, a plan view and a sectional view, the latter on the line 15—15 of Figure 14, of the oscillating switch reversing element.

As shown in the drawings, the switch mechanism is enclosed by and supported on an insulating base comprising top and bottom members 21, 20, respectively. 25 (Figure 5), designates a hollow, rectangular frame that is supported in the base and projects therefrom (Figures 1, 3, and 4). It has an inwardly extended base 26 provided with an aperture 27 which receives a rivet or stud 28 to hold the frame in place. The inner end of the base is reduced in width and is formed with upwardly extending, rearwardly curved arms 29, 30 that are provided with registering apertures 31. The rear wall of the frame 25 is provided with an opening 32 (Figures 1, 7, and 8), through which extends a universally movable actuating device 33, which, as shown, has the form of a tube, and is provided with a flat seat or flange 35 adapted to engage a corresponding normally parallel seat portion 36 of a plunger 37 (Figure 6). Said plunger 37 has a horizontal guide portion comprising a narrow member 40 that is joined to the vertical seat portion 36 by a wider horizontal member 41, and the guide member fits and slides on the base 26 of the frame 25.

45, 45 designate fixed switch terminals that cooperate with a swinging switch blade which comprises a yoke shaped member 47 that is pivoted by the pivot pin 48 which extends through the apertures 49 of the arms of the blade and through the apertures 31 of the arms 29, 30 of the frame 25. The U-shaped terminal member 46 of the switch

blade fits over the yoke shaped blade 47. It is insulated therefrom by the L-shaped insulating strips 50 which together with said terminal member, are fixed to the swinging 5 blade, by ears 51 that are integral with the switch blade 47 and are folded inwardly over the insulating strips 50, which latter, in turn, overlie the closed portion of the switch blade 47. The said closed portion of 10 the U-shaped switch blade 47 is formed with an opening 52 which registers with, but is smaller than, an opening 53 in the closed portion of the U-shaped terminal 46, as best shown in Figures 9 and 10. The openings 15 52, 53 are provided for the passage of the shank 54 of a throw-over plunger (Figure 13) that is provided with a head 55 formed with a downwardly opening notch 56 for a purpose hereinafter to be described.

20 60 designates a rocking reversing member for the switch blade. It is pivoted on the pivot pin 48 and lies between the lower ends of the arms of the blade. Said reversing member comprises two parallel plates 61 25 which are connected by a lower cross member 62 and upper cross members 64, 65 integral with said plates; and the plates are provided with registering openings 61' for the passage of the pivot pin 48. The lower 30 cross member 62 forms inwardly and outwardly facing shoulders 66, 67, respectively, and the upper cross member 64 forms an outwardly facing shoulder 68, for purposes hereinafter to be described. One of the 35 plates 61 is provided with an extension 69, forming a downwardly facing shoulder 70. Both of said plates are formed at their outer sides with guide extensions 71 for a purpose to be hereinafter described.

40 75 designates a controller member which comprises an outwardly extending shank 76 and two inwardly extending fork arms 77, 78, respectively, that are formed at their inner ends with recesses 79, 80, respectively.

45 The said controller member is provided between said shank and fork arms with a cross arm 81 that is flat on its outer surface 82 to fit flat against the inner face of the flange 36 of the operating plunger 37. Said flange 50 36 of the plunger is provided with a central guide opening 83 outwardly through which the shank 76 of the controller member loosely extends and by which it is guided in operative movement.

55 The controller member 75 is held in normal position when the actuating device 33 is in its normal horizontal position with the flat face 82 of its cross arm 81 in contact with the flange 36 of the plunger by a spring 85, 60 coiled between its ends, the outer end of which extends through an opening in the controller member and the inner transverse portion 87 of which extends through registering openings 88 in the upstanding arms 65 29, 30 of the frame 25. The said arms 29, 30

constitute a fixed abutment for the spring in such manner that the outer or free end of the spring acts normally to hold the controller member in the position shown in Figure 1 and to return said member from the 70 position indicated in Figures 7 and 8 to that shown in Figures 1 and 4. The spring 85, thus acting on the controller member serves, through the plunger 37, to restore the actuating member to its position when the latter 75 is released.

The controller member 75 controls the operation of the switch reversing device 60 when the actuating handle is swung or forced inwardly by the engagement of the 80 recessed ends 79, 80, of the arms 77, 78, respectively, with the shoulders 68, 67, respectively of the switch reversing member, as indicated in Figures 1, 4 and 15. The notched end of the head 55 of the throw-over plunger engages with the cross member 65 of said reversing member, as best shown in Figures 1, 4, 7, and 8. A spring 90 surrounding the shank of said throw-over plunger and interposed between the closed 90 portion of the yoke shaped switch blade 47 and said head 55 serves expansively to normally hold said switch blade at one of the extreme positions of its movement, as indicated in Figures 1 and 4, and also to throw the switch blade quickly from one position to the other when said inner end of the plunger swings past the plane of the pivot 95 48. The spring 90 and its associated plunger, therefore, constitutes means for 100 yieldingly holding the switch blade at the extreme positions of its movement and for automatically and quickly throwing the blade past its center of movement.

One of the upstanding arms of the frame 105 25 (the arm 30 shown) is provided on its inner face with a stop lug 92 which is adapted to be engaged either by the shoulder 70 of the projection 69 of the switch reversing device in one extreme position of the switch 110 blade, as shown in Figure 1, or to be engaged by the shoulder 66 of the cross member 62 of said reversing device in the other extreme position of the blade 28, as shown in Figure 4.

The operation of the switch mechanism is 115 as follows:

In Figures 1, 2, and 3, the actuating device 33, the controller member 75, and the switch reversing member 60 are in the normal positions which they occupy when the switch is open. In these positions of the parts the recessed portion 80 of the fork arm 78 of the controller member is engaged with the shoulder 67 of the lower cross member 62 of the rocking switch reversing member, and the other fork arm 77 of the controller member lies between the guide projections 71 of the laterally separated plates 61 of said reversing member. In the position of 120

125 65 70 75 80 85 90 95 100 105 110 115 120 125 130

the parts shown in Figure 1 the spring 90 of the throw-over plunger acts expansively between the head 55 of the plunger 54 and the closed portion of the switch blade to hold the latter away from the fixed switch terminals 45 thereof. The opening movement of the switch is limited by engagements of horns 95 on the lower ends of the arms of the switch blade with a shoulder 96 formed by the inwardly facing edge of the top wall of the frame 25. The movement of the reversing member 60, in the position of the parts shown in Figure 1 is limited by engagement of the shoulder 70 with the stop lug 92 of the arm 30.

If, now the actuating member 33 be either pushed inwardly or be swung about its pivot, it will have the effect to turn the reversing member in the direction indicated by the arrow on Figure 1. In thus turning the reversing member the lower end of the plunger 54, seated on the cross piece 65 of the reversing member, is caused to move outwardly towards the actuating device 33 in a curved path. This movement of the plunger causes it to be extended through the openings in the closed end of the switch blade and places the spring 90 under compression. When the lower or headed end of the plunger passes the center of its arc of movement, or just after it has passed the plane of the pivot pin 48, the power of the spring, under compression, serves to quickly throw the switch blade downwardly with the terminal blades 46 into contact with the fixed terminals 45 and thereby closes the switch (Figure 4). The closing movement of the switch blade is limited by engagement of a second pair of horns 98 with shoulders 99 formed on the inner edge of the bottom wall of the frame 25 at the sides of the switch blade supporting arms 29 and 30. Movement of the reversing member in the direction which it is moved in the closing movement of the switch is arrested by contact of the shoulder 66 of the cross member 62 of said reversing member with said stop lug 92, as indicated in dotted lines in Figure 4. After the switch has thus been moved from open to closed position and the actuating device 33 released the spring 85 serves to restore the controller member 75 and therethrough the said actuating device 33.

The operation of the parts to open the switch from its closed position shown in Figure 4 is the reverse of that just described. From an inspection of Figure 4, it will be noted that the recessed end 79 of the upper fork arm 77 of the controller member is in contact with the shoulder 68 of the reversing member so that inward movement of the controller member acts to rock the reversing member and to carry the headed end of the plunger 54 inwardly past

and that when said inner end of the plunger has passed said plane the compression of the spring 90 serves to quickly throw the switch blade upwardly out of contact with the fixed terminals 45. The opening movement of the blade is arrested by contact of the horns 95 with the shoulder 96 above referred to, and the rocking movement of the reversing member 60 is arrested by contact of the shoulder 70 thereof with the stop lug 92 hereinbefore referred to.

It will thus be observed that the same movement of the actuating device 33, whether it be a swinging movement in all the directions in which it is capable of swinging or whether it be an endwise movement, has the effect to operate the controller member 75 and the reversing member 60 in a way to swing the inner end of the throw-over plunger 54 past the plane of the pivot member 48 on which the reversing member rocks, so that the spring 90 may quickly throw the switch blade 47 from either limit of its movement to the other, regardless of whether the switch be open or closed.

The elements for conducting the current from the switch elements to the center and shell conductors 105, 106, respectively, for the lamp may be of any known or preferred form and need not be further described.

I claim as my invention:

1. In an electric switch, the combination with a swinging switch member and its co-operating fixed terminal, a rocking reversing device, a spring controlled plunger operatively connected between said reversing device and said swinging switch member, and a single actuating device normally disconnected from and adapted for alternate operation on opposite side of said reversing device for giving alternate rocking movement thereto.

2. In an electric switch, the combination with a swinging switch member and its co-operating fixed terminal, a rocking reversing device, a spring controlled plunger operatively connected between said reversing device and said swinging switch member, a controller member mounted for tipping and reciprocating movement and operatively connected to the reversing member, and means for tipping and reciprocating said controller member.

3. In an electric switch, the combination with a swinging switch member and its co-operating fixed terminal, a rocking reversing device, a spring controlled plunger operatively connected between said reversing device and said switch member, a controller member mounted for tipping and reciprocating movement and operatively connected at one end to the reversing member, and an actuating device mounted for universal swinging movement having a flat

plane face adapted for co-operative action with the controller member.

4. In an electric switch, the combination with a swinging switch member and its co-operating fixed terminal, a rocking reversing device, a spring controlled plunger operatively connected between said reversing device and said swinging switch member, a frame on which said swinging switch member is mounted, a spring actuated plunger cooperating with said swinging switch member, said frame being provided with stop shoulders adapted to cooperate with the swinging switch member to arrest it at each extreme limit of its movement, a controller member coacting with said reversing member on opposite sides of the rocking axis, and an actuated member coacting with said controller member.
- 20 5. In an electric switch, the combination with a swinging switch member and its co-operating fixed terminal, a rocking reversing device, a spring controlled plunger operatively connected between said reversing device and said swinging switch member, a frame on which said swinging switch member is mounted, said frame being provided with stop shoulders adapted to cooperate with the swinging switch member to arrest it at each extreme limit of its movement, a controller member mounted for tipping and reciprocatory movement and adapted at one end for coaction with the reversing member, said controller member being provided at its other end with a flat face and an actuating member mounted for universal swinging and axial movement and adapted to co-operate with the flat face of the controller member.
- 30 6. In an electric switch, the combination with a frame provided with arms, and fixed terminals, of a swinging switch member co-operating with said fixed terminals and pivoted to said arms, a rocking reversing member mounted to rock on the swinging axis of the switch member, spring means to connect said reversing member to the switch member to throw the latter from one extreme position to the other, a controller member mounted on the frame for tipping and reciprocatory movement, and means for actuating said controller member.
- 45 7. In an electric switch, the combination with a frame provided with arms, and fixed terminals, of a swinging switch member co-operating with said fixed terminals and pivoted to said arms, a rocking reversing member, spring means to connect said reversing member to the switch member to throw the latter from one extreme position of its movement to the other, a controller member mounted on the frame for tipping and reciprocatory movement, said controller member being provided with a straight faced portion, a plunger slidable in said frame

and provided with a flange to engage said straight faced portion, and an actuating device pivoted on said frame for universal swinging movement and having a flat seat to engage said plunger flange.

8. In an electric switch the combination with a swinging switch member, of a rocking reversing member, a spring controlled plunger engaging a shoulder on the reversing member and slidably freely through the switch member, with a spring surrounding the plunger and interposed between the switch member and a shoulder on the plunger, and means to alternately engage said reversing member on opposite sides of its rocking axis for imparting alternate rocking movement thereto.

9. In an electric switch, the combination with a swinging switch member, of a rocking reversing member, a spring controlled plunger engaging a shoulder on the reversing member and slidably freely through the switch member, with a spring surrounding the plunger and interposed between said switch member and a shoulder on the plunger, a controller member mounted for tipping and reciprocating movement relatively to said frame and provided with arms adapted for engagement with shoulders on the reversing member at opposite sides of its pivot, and means for giving reciprocating and tipping movement to said controller member.

10. In an electric switch, a frame, a U-shaped switch blade pivoted to said frame, a rocking reversing member pivoted on the swinging axis of said blade, a plunger engaging a shoulder on said actuating device and slidable through the U-shaped blade, with a spring surrounding it and interposed between said blade and a shoulder on the plunger, horns on the switch blade adapted to engage shoulders on the frame to arrest said blade at both limits of its movement, and a single device normally disconnected from said reversing member to alternately rock said reversing member on its pivot.

11. In an electric switch, a frame, a U-shaped switch blade pivoted to said frame, a rocking reversing member, a plunger engaging a shoulder on said member and slid able through the U-shaped blade, with a spring surrounding it and interposed between said blade and a shoulder on the plunger, horns on the switch blade adapted to engage shoulders on the frame to arrest said blade at both limits of its movement, a controller member mounted for tipping and reciprocatory movement on said frame and provided with forked arms which engage shoulders on the reversing member at opposite sides of its pivotal axis, and means for actuating said controller member.

12. In an electric switch, a frame, a U-shaped switch blade pivoted to said frame,

- a rocking reversing member pivoted to the swinging axis of said blade, a plunger engaging a shoulder on said actuating device and slidable through the U-shaped blade, with a spring surrounding it and interposed between said blade and a shoulder on the plunger, means to arrest the switch blade at both limits of its movement, a controller member mounted for tipping and reciprocatory movement on said frame and provided with forked arms which engage shoulders on the reversing member at opposite sides of its pivotal axis, said controller member being provided with a straight faced portion, a plunger slidable in the frame and having a straight portion adapted for engagement with the straight portion of the controller member, and an actuating member mounted for universal swinging movement in the frame, said controller member being provided with a shank which extends through a guide opening in said flange of the plunger and into the actuating member.
13. An electric switch comprising a base, fixed terminals mounted thereon, a swinging
- switch blade supported on the base for contact with the fixed terminals, a rocking reversing device mounted on the swinging axis of said blade, a spring actuated throw-over plunger connecting said reversing device to said switch blade, and means to alternately act on said reversing device on opposite sides of its axis for alternately rocking said reversing device.
14. An electric switch comprising a base, fixed terminals mounted thereon, a swinging switch blade supported on the base for contact with the fixed terminals, a rocking reversing device mounted on the swinging axis of said blade, a spring actuated throw-over plunger connecting said reversing device to the switch blade, and an actuating device mounted for universal swinging movement on the base for actuating said reversing device.

In testimony whereof I claim the foregoing as my invention, I hereunto append my signature at Chicago, Illinois this 25th day of June, 1919.

ERNST G. K. ANDERSON.
